(57) **CLAIM**

The ornamental design for a skimmer box lid mould kit unit assembly, as shown and described.

DESCRIPTION

FIG. 1 is a top perspective view of the skimmer box lid mould kit unit assembly;

FIG. 2 is a back view thereof;

FIG. 3 is a bottom view thereof;

FIG. 4 is an exploded back view thereof;

FIG. 5 is an exploded bottom view thereof;

FIG. 6 is an exploded front view thereof;

FIG. 7 is an exploded left side view thereof;

FIG. 8 is an exploded right side view thereof;

FIG. 9 is an exploded top perspective view thereof;

FIG. 10 is a front view thereof;

FIG. 11 is a left side view thereof;

FIG. 12 is a right side view thereof;

FIG. 13 is a top view thereof;

FIG. 14 is a top perspective view of a slot former for the skimmer box lid mould kit unit assembly;

FIG. 15 is a back view thereof;

FIG. 16 is a bottom perspective view thereof;

FIG. 17 is a bottom view thereof;

FIG. 18 is a front view thereof;

FIG. 19 is a left side view;

FIG. 20 is a right side view;

FIG. 21 is a top view;

FIG. 22 is a top perspective view of a retention plug for the skimmer box lid mould kit unit assembly;

FIG. 23 is a back view thereof;

FIG. 24 is a bottom perspective view thereof;

FIG. 25 is a bottom view thereof;

FIG. 26 is a front view thereof;

FIG. 27 is a left side view thereof;

FIG. 28 is a right side view thereof; and,

FIG. 29 is a top view thereof.
